UNITED STATES PATENT OFFICE

ADOLF LETTERMANN, OF BERLIN-TEMPELHOF, GERMANY

DEVICE FOR TAKING FOOT-IMPRESSIONS

Application filed December 7, 1929, Serial No. 412,502, and in Germany December 11, 1928.

This invention relates to a device for taking foot impressions. In order to do away with the complaints and organic alterations resulting from a flat-foot, splay-foot or stretched foot a great number of foot supports have been constructed. These supports are either manufactured uniformly according to the size of the foot or adapted to the foot by measuring the treading surface.

10 These measurements are, for instance, carried out in such a way that the patient is made to set his foot with the sole painted upon white paper, or the patient is made to step upon a semi-set mass of plaster of Paris.

15 However in both cases no image of the burdened sole is obtained permitting of conclusions as to the degree of sinking of the foot caused by the load. The correct image can only be obtained by exerting pressure upon 20 the sole from below upwards and thereby removing the sinking caused by the relaxing of the ligaments.

A pneumatic chamber would be capable of solving this problem, but steady walking on such a support would be impossible for various reasons.

Now I have found that an impression of a sole may well be produced representing an exact copy of the burdened sole showing the 25 reposition of the bone *p* sinking under the load.

A device for taking an impression of such kind is illustrated in annexed drawings, of which Fig. 1 is a plan view, and Fig. 2, a 30 vertical cross section of a device embodying my invention.

The device consists of a flat chamber having an elastic envelope *a*, the plan view corresponding to the outline of a human foot. 40 This chamber is filled with a molten mass *b* which solidifies after some time, such as a mixture of paraffin and wax.

When the patient steps upon this chamber filled with the molten mass, and remains upon 45 it until the mass has solidified, the mass in the chamber is compressed by the weight of the body so that it forces upwards the least burdened parts i. e. the very ones sunk by loosening of the ligaments. An excessive 50 tension of the relaxed ligaments cannot occur.

The chamber may also be provided with a flexible pipe, as *c* in Fig. 1, through which the molten mass may be injected, under pressure, into the evacuated loaded chamber.

The described device permits of taking 55 measure in the boot itself. Hereto, besides the impression of the foot, the exact form of the inner sole of the boot or shoe is reproduced. The impression may be used, with or without the envelope, as a permanent foot 60 support.

I claim:—

1. A device for taking foot impressions, comprising a flat closed elastic chamber having the outline of a human foot and filled 65 with a liquid mass which solidifies in a short time.

2. A device for taking foot impressions, comprising a flat closed elastic chamber having the outline of a human foot and being 70 filled with a liquid mass which solidifies in a short time, and a flexible pipe communicating with the said chamber.

3. The method of taking impressions from a flat, splay or stretched foot of a person, comprising filling a plastic mass which solidifies in a short time into a flexible chamber having substantially the outline of the foot, putting this chamber into a boot or shoe, and shaping the said chamber by making the person walk 80 upon the said chamber.

In testimony whereof I affix my signature.

ADOLF LETTERMANN.
